UNITED STATES PATENT OFFICE.

CHARLES W. BAILEY AND JOHN HAMMOND STEWART, OF LYNN, MASSACHUSETTS;
SAID BAILEY ASSIGNOR TO SAID STEWART.

CUTTING-MACHINE.

1,346,626.

Specification of Letters Patent. Patented July 13, 1920.

Application filed March 25, 1915, Serial No. 17,009. Renewed March 16, 1920. Serial No. 366,438.

To all whom it may concern:

Be it known that we, CHARLES W. BAILEY and JOHN HAMMOND STEWART, both citizens of the United States, and residents of Lynn, 5 in the county of Essex and State of Massachusetts, have invented certain new and useful Improvements in Cutting-Machines, of which the following is a specification.

The present invention relates to cutting machines, and particularly such as are adapted to cut leather and like materials used in making parts which enter into the construction of boots and shoes. Our object is to produce an automatically acting machine capable of skiving, or cutting on a bevel, such articles as counter stiffeners and the like; and particularly to perform the operation known in the art as "end clipping," which is that of cutting a wide bevel 20 on the ends of a counter stiffener blank. With this object in view, we have developed an operative embodiment of our invention in a machine having knives arranged to act on the two ends of a counter blank simultaneously and a work support designed to hold the blanks at such inclinations to the plane or planes in which the knives operate, and with such capacity for adjustment, that the ends of the blank may be trimmed or 25 clipped with the desired angle of bevel; and having a feeding contrivance for the blanks, and other novel features of construction hereinafter particularly pointed out in connection with the accompanying drawings.

As the invention consists in a machine and not in the method or operation performed by its use, we declare that, therefore, we do not limit the scope of the invention to an apparatus or means for performing only the 30 operation mentioned, nor to only the particular embodiment of the machine herein illustrated and described, as it is within our contemplation to adapt the machine, with or without modification, to other uses, and 35 to modify the structural features of the machine in ways which may increase its efficiency for its designed purpose, or to adapt it to serve other purposes, within the scope of the appended claims.

50 In the drawings,

Figure 1 represents the machine in front elevation.

Fig. 2 is an end elevation of the machine as seen from the right of Fig. 1.

55 Fig. 3 is a plan view of the machine.

Fig. 4 is a central longitudinal section of the machine.

Fig. 5 is a central transverse section of the machine.

Fig. 6 is a plan view of the bed and work 60 supporting tables of the machine, the parts above being removed, and those parts which cross the plane of the drawing being shown in section.

Fig. 7 is a plan view of the work-pressing 65 means and the holder therefor detached.

Fig. 8 is a plan view of the knife-carrying slide.

Fig. 9 is a cross section of the same on line 9—9 of Fig. 8. 70

Fig. 10 is a plan view of the knife block.

Fig. 11 is a front elevation of the knife block.

Fig. 12 is an elevation of the slide shown in Fig. 8, representing the same as viewed 75 from the left of Fig. 8.

Fig. 13 is an inverted plan view of the detachable supporting plate for the blank.

Fig. 14 is an elevation of the same.

Fig. 15 is a detail view on an enlarged 80 scale of the holding latch for such plate, this view being a section on line 15—15 of Fig. 13.

Fig. 16 is a plan view of the forming plate for the blank. 85

Fig. 17 is a plan view of a modified forming plate.

Figs. 18 and 19 are sectional views of said plate on lines 18—18 and 19—19, respectively, of Fig. 17. 90

Figs. 20 and 21 are respectively a plan view and a longitudinal section of a counter blank after being operated upon in this machine.

Fig. 22 is a longitudinal sectional view of 95 the work support and an elevation of the work centering device.

Reference is first made to Fig. 5 in order best to give a comprehensive view of the main parts and operation of the machine. 100 The work piece or blank 25, is supported at its center on a rigid block 26 and is firmly held against the same by a presser foot 27. The ends of the blank extend over forming plates 28 which are supported on supporting plates 29. This machine is double and has two sets of work supporting elements and knives and associated parts adapted to act simultaneously on the two ends of a work piece. The parts on each side of the 110

forward and rear center line of the machine are mainly duplicates of each other, and in all instances where parts are duplicated, the same reference characters are used for both 5 duplicate parts. With this explanation I will proceed to describe the parts at one side of the above named center line, without referring in each instance to the duplicate parts on the opposite side of such line. The 10 supporting plate and with it the forming plate may be adjusted to various heights and inclinations in order to govern the angle and extent of the bevel on which the end of the blank is cut, by means of wedges 15 30 and 31 underlying the outer and inner end portions of the supporting plate respectively and carried by the respective slides 32 and 33 which pass laterally to the outer side of the machine frame.

20 The cutting knives are represented by 34 and each moves from a position at one side of and near the longitudinal center line of the machine toward the adjacent side of the machine, in performing its operative stroke. 25 The knife is fixed to a knife block 35 which is carried by a slide 36 which latter is provided with ears 37 supporting a pivot pin 38 by which the slide is connected to a link 39. Such link in turn is connected to an 30 operating arm 40 formed as part of a lever pivoted on a stud 41 and having a second arm 42 which is connected by a link or connecting rod 43 with an operating crank pin 44 on a crank 45 carried by a shaft 46. The 35 knife carrying slide 36 is guided by guide rods 47 to travel rectilinearly, and the work supporting plate 29 is adjusted by means of the wedges or lifters 30 and 31 so as to cause a greater or less extent of the blank end to 40 cross the line in which the knife edge is so caused to travel, and also to regulate the angle which the end portion of the blank makes with this line. The line of cutting travel of the knife is indicated by the broken 45 line *a*—*b* in Fig. 5.

The blank which is shown in position for operation in Fig. 5 is shown completed in Figs. 20 and 21. This blank is a counter stiffener blank which has been, or may have 50 been, already skived at its opposite edges 25^a and 25^b, but the ends of which, at least in part, have too great thickness. After the blank has been placed in the machine and held as above described in relation to the 55 knives, it emerges with its ends beveled at 25^a and 25^b, the extent and inclination of the end bevels being determined as above described by the adjustment of the lifters or wedges 30 and 31.

60 I will now describe the mechanical construction of the illustrated machine. The block 26 and slides 33 are all supported on a table 48 which forms the top wall of the machine base or frame, such base or frame being a box-like structure inclosing a space for

mechanism and having openings in its upright walls. It is supported upon legs 49 or may be supported or mounted in any other desired manner.

Power for operating the machine is delivered to a shaft 50 from one of the two pulleys 51, 52 which are shown in Fig. 6 as mounted on said shaft, one of these pulleys being fast and the other loose. The shaft also has a hand wheel 53 for use in special 70 circumstances, but which is not employed in the automatic operation of the machine. This shaft carries a miter gear 54 which meshes with a complementary miter gear 55 on a short shaft 56 which runs from front 75 to rear and is shown in end view in Figs. 1 and 5. A pinion 57 on shaft 56 meshes with a gear 58 on one of the crank shafts 46, and the said pinion also meshes with an intermediate gear 59 on a central shaft 60, and 80 through the intermediate gear drives a gear 61 on the second shaft 46. The gears 58 and 61 are thus rotated in unison in opposite directions and the cranks 45 carried by the two shafts 46 oscillate the two knife operating 85 levers 40 simultaneously but in relatively opposite directions so that both knives approach the center of the machine at the same time and both recede at the same time. The pivot rods 41 for the knife operating levers 90 are mounted in the front and rear vertical walls of the base frame as shown in Fig. 1.

The intermediate shaft 60 previously mentioned controls the raising and lowering of the frames which carry the presser foot 27, 100 and also carry the guides for the knife carriers 36. Each of these frames consists of two upright rods 62 which pass through the table 48, a crossbeam 63 within the base frame below the table, and a crossbeam 64 105 above the table. The beams 64 are on respectively opposite sides of the transverse center line of the machine and each connects one pair of the rods 62, and the lower crossbeams are similarly arranged. Each of the 110 frames so formed supports one of the two guide rods 47 on which the knife carriers are mounted, each end of such guide rod being secured in a block 65 which is mounted on one of the rods 62 below the adjacent end 115 of the upper crossbeam 64. The upright rods pass through the beams 64 and are provided with nuts 66. Beneath the blocks 65 are capstan headed adjusting and locking nuts 67, 68, screwed upon the rod 62, which 120 adjust the springs 69 on each rod 62 between the table and the respective locking nut 68. All of such springs together are sufficiently powerful to elevate the two frames and the knife carriers and presser foot far 125 enough above the work supporting plates to admit blanks readily. The amount of possible rise of these frames is limited, and the downward movement of the frames is effected at the proper time, by cams 70 upon 130

the shaft 60, each of which cams engages a roll 71 carried in a holder 72 on the lower crossbar 63 immediately adjacent to such cam. The outline of the cams 70 is shown dotted in Figs. 1 and 5, and both cams are shown in section in Fig. 4. The beams 64 of the two frames are connected by a cross-tie 73 having flanges 74 at its ends, which are fastened in any desired way mechanically to the beams 64. Said cross-tie is also formed with a central opening 75, shown in Fig. 4 and in the tie near the ends of this opening are firmly fixed two rods 76 on which the presser foot 27 and a yoke 77 are adapted to slide, said presser foot and yoke having guiding sleeves 78 which receive the guide rods, as shown in Fig. 4, the presser foot being below the cross-tie and the yoke 77 being above and bridging the opening 75 therein. The presser foot and yoke are secured together and at the same time spaced apart at the required distance by shouldered tie rods 79 and nuts 80. Springs 81 are mounted on the upper ends of the guide rods 76 between the yoke 77 and adjustable nut abutments 82 threaded on the rods. The springs permit the structure composed of the presser foot 27, the yoke 77, and the tie rods 79 to be raised against a yielding resistance, and they hold the presser foot with a firm elastic pressure, the intensity of which can be regulated by the nuts 82, against the work when brought down upon the same.

From the foregoing description it will be seen that the cams 70 and springs 69 control the movements of the frame which raise and lower the presser foot. The same movements also raise and lower the knife carriers for the reason that the carrier guide rods 47 are mounted in the same frame.

Reference is now directed to Figs. 8, 9, and 12 for a showing of one of the knife carriers and to Figs. 10 and 11, as well as Fig. 5, for illustration of one of the knife blocks. The carrier 36 is a bar or beam which extends across from one guide rod 47 to the other and has bearings 83 at opposite ends to embrace the rods. The bearings are formed with tubular extensions, as shown in Fig. 8, and are slotted or split in their outer sides, being provided with adjusting screws 84 for taking up wear. As appears from Fig. 8 each carrier is equipped with two pairs of ears 37 for pivotal connection with the part 39, which has been already described as a link which connects the carrier with its operating lever 40. This part or link is of composite construction, consisting of a yoke 39, shown best in Fig. 3, the ends of which are pivoted to the pins 38, and a rod 39^a which is screwed into the central part of the yoke and is clamped by a lock nut 85. The rod 39^a has an open notch or hook 86 adapted to receive the pivot stud 87 carried by the operating lever 40, which pro-

vides the connection between said lever and the link; and said rod also has a handle 88 by which it can be lifted so as to disconnect the notch from the stud 87 for the purpose of enabling the carrier to be moved independently of the lever, or for other purposes.

The knife carrying block 35 is made as a hollow casting having an inclined lower wall, as shown in Fig. 5, to which the knife 34 is detachably secured. The cutting edge of the knife projects beyond the adjacent side wall of the block, and such wall is made concave to provide a recess 89 which facilitates the disposal of the chips cut from the work. The concavity or recess 89 is made without any sharp corners at its bounding edges, whereby the emergence of the chips is facilitated and no chance is afforded for the chips to lodge. Said block also has flanges 90 at its opposite ends for attachment to the carrier, said flanges being adapted to pass into the recess afforded between the under side of the carrier, a shoulder 91 on the carrier, and a clamping piece 92 which is fastened to the under side of said shoulder by an attaching bolt 93. The knife block when being mounted upon the carrier is moved horizontally until its flanges enter this recess and bring up against a stop pin 94 on the clamp 92. Then the bolt 93 is tightened up to bind the block. It is to be understood that the carrier is of the same form at both ends and is equipped with two clamps and stops, both of which are constructed and arranged as above described.

Referring again to Fig. 5 there will be found means for pressing down the work immediately in advance of the action of the knife and causing the work to conform to the supporting surface of the forming plate. The embodiment of means here shown consists of fingers 95 of which there is a comparatively large number adjacent to each knife, the fingers of each set being pivoted on a rod 96 carried by a holder 97, such holder being shown in plan in Fig. 7, in elevation at the left hand of Fig. 2 and in Fig. 1, and in section in Fig. 5. The two ends of the holder 97 are depressed below its middle portion and are adapted to lie beneath the extension of the bearing sleeve 83 on the knife carrier. Each of such ends has a notch 98 adapted to be slipped over and to receive the shank of the holding screw 99 which is tapped into the said extension. By setting up the screws 99 on opposite ends of the knife carrier, the finger holder is clamped to the carrier and supported thereby. The end portions of said holder also have lugs 100 containing set screws 101, which are adapted to bear against the knife carrier and adjust the location of the holder and fingers in respect to the knife. The raised central part of said holder

- 4
- is well above the fingers and its under surface is also above the upper termination of the concavity 89 of the knife block, thereby providing an ample channel for escape of chips.
- 5 A cover plate 102 overlies the fingers and prevents the chips cut from the work from falling between and clogging the fingers. Said plates may be secured in any suitable way to the finger holders.
- 10 As appears best from Fig. 5 the fingers extend from the pivot rod toward the adjacent knife and terminate slightly below the edge of the knife and close to the same. Each finger has an outwardly extending
- 15 arm or tail piece 103 which rests on an abutment 104, the latter being a bar underlying all the arms of the series and supported at its opposite ends by rods 105 which pass through portions of the holder 97 and have
- 20 heads 106 resting on the holder. The tail extensions 103 of the fingers are resilient so that the fingers may yield in passing over the stock, but they are at the same time stiff enough to cause the fingers to apply a powerful pressure to the work.
- 25 The function of these fingers is to press the work piece against the forming plate immediately in advance of the knife, thereby preventing the end of the piece from
- 30 being lifted up by the knife and cut off too short, but at the same time the fingers are adapted to yield when passing over the rising end of the work where the upper surface of such end passes above the path of the
- 35 knife edge. The fact that there are many fingers acting on the same work piece, each finger being movable independently of the others and overlying only a narrow portion of the work piece enables the fingers to
- 40 yield independently for local irregularities in the surface of the work and also causes the under surface of the work to conform to the surface of the forming plate 28.
- 45 Springs 107 surround the rods 105 and react between the body of the holder and collars 108 adjustably mounted on the rods, thereby normally holding the abutment bar 104 in its lowermost position but permitting the same to be raised when necessary.
- 50 The formation which is given to the skived or clipped surface of the work is determined by the forming plate in combination with the fingers 95. Where such plate has a plane supporting surface, as is the
- 55 case with the plate 28 shown in Figs. 5 and 16, the knife forms a plane surface making an acute angle with the opposite surface of the work, but when the forming plate is otherwise shaped, other results are produced
- 60 in the work. For instance, supposing it is desired to form the skived surface with a convex curvature, a forming plate such as the plate 28 shown in Figs. 17, 18, and 19 is used. This plate has a concaved re-
- 65 cess 109, the outline of which conforms to

the outline of the work piece, and the surface of which is the complement of the surface which it is desired to produce upon the work. The fingers in passing over the work press the end portion thereof into the recess 109 causing the under surface of the piece to conform exactly with the surface of the recess and bending the exposed surface of the work out of its normal form. The surface left by the knife, although plane as long as the work is so distorted by the fingers, becomes of the desired curvature when the work piece is allowed to resume its normal shape. By selecting suitable forming plates the work may be cut with any desired contour of its skived surface.

The adjustment of the lifter wedges 30 and 31 for the supporting plates 29 is effected by screws 110 and 111, the former being engaged with a lug 112 on the slide 32 and with a lug 113 on a frame 114 which is fixed to the table of the machine and is undercut to provide a guideway for the slide. The other screw passes through a lug 115 on the slide 33 and is screwed into the side of the base. These screws have adjustable nuts 116 threaded upon them by which the adjustments are affected in an obvious manner. The inner end member 117 of the frame 114 provides an abutment for the outer edge of the supporting plate 29, while the anvil block 26 provides the abutment for the opposite edge of plate. Thus displacement laterally of the plate is prevented. The supporting plate is further retained in place and firmly held against the adjusting wedges by means of latches 118, see Figs. 13, 14, and 15, which are mounted at the lower ends of sleeves 119 at the front and rear edges of the plate and are adapted to be turned so as to underlie shoulders 120 in the table of the frame. Each latch has a shank 121 and a head 122 contained in the sleeve and acted on by a spring 123 which surrounds the shank and presses upwardly against the head, reacting against a shoulder in the lower end of the sleeve. These latches do not prevent the plates from being tilted and raised by the wedges, but they hold the plates firmly against the wedges.

The table of the base, the slides 32 and 33, and the frame 114 have registering openings through which the operating levers 40 pass.

The blanks to be operated on by the machine are laid by the operator one at a time on a table 124 at the front of the machine, shown in Figs. 4 and 6, between adjustable gages 125 and immediately in rear of upstanding pins 126. The blanks are then carried by an intermittently traveling endless conveyer and advanced by a succession of steps to the operating position. The conveyer consists of two chains 127 passing from front to rear across the table of the

machine base in guide troughs provided for them therein and also in the block 26, around 5 guide pulleys 128 at the rear of the machine, thence downwardly and around lower guide pulleys 129, thence forward beneath the machine, around a third set of guide wheels 130, and up to the driving sprockets 131, which are mounted directly under the location in which the work blanks are placed. 10 The conveyer chains carry pushers 132 and grippers 133. The pushers are upstanding fingers secured to or formed upon certain links of the chain at suitable distances apart, and the grippers are springs fixed 15 upon links adjacent to those from which the pushers rise and projecting from their points of attachment forwardly, with respect to the direction in which they travel. When the chain is straight the gripper 20 spring is pressed against a link in advance of the one to which it is attached, but when the chain is bent in passing around the driving sprocket or a pulley, the free end of the spring is lifted relatively to the link on 25 which it previously pressed. This action of the gripper, effected by the bending of the chain, is made use of to effect an automatic grasping and releasing of the work. Thus the location of the place where the blanks 30 are laid by the attendant of the machine is at the point where the springs are still raised from the adjacent forward links in passing around the sprockets 131. The chains pass under the blank almost in contact with the 35 under surface thereof, and the springs pass over the blanks until the pusher fingers come into contact with the blank. By the time the pushers have engaged and advanced the blank, the chain has become so far straightened as to bring the adjacent spring gripper 40 against the work. After the conveyer has placed the work in the operating position, and paused, it carries it on, and in passing around the rear guide wheel 128 the grippers are again relaxed and the blank is allowed to fall into a receptacle placed beneath. This device constitutes a very simple means for automatically grasping and 45 releasing the work pieces and making it unnecessary for the operator to place the pieces accurately on the conveyer.

A means for securing the accurate location of the work pieces and causing them to abut squarely against the pusher fingers is 50 provided by a presser which is shown in Figs. 2, 6, and 22 (being omitted from the other figures for clearness). This presser is constituted by a bar 134 and a forked arm 135 which rest on the tables 124 and 48, respectively, between the chains of the conveyer, and are pressed upon by springs so that they may yield to permit the blanks to pass under them, and at the same time press on and hold back the blanks in equal engagement with the pusher fingers of both

chains. A rod 135^a which is supported and held rigidly by posts 136 at each side of the chains, so as to bridge over the path of feeding, has fixed on it a frame consisting of arms 136^a and 136^b, the latter having a 70 housing 136^c. Bar 134 has slots 134^a in its ends which admit pins 136^d on the arms of the frame, and a spring 136^e is confined between the bar and frame arm 136^b. The forked bar 135 has a slot 135^b containing a 75 pin 135^c on arm 136^b, and is pressed down by a flat spring 135^d, fastened at one end of arm 136^b and bearing at its opposite end on the bar 135. The branches of this bar lie across the anvil block 26 on each side of the 80 presser 27.

The means for driving the conveyer with an intermittent motion and causing it to stop when each work piece is in the proper position to be operated on, consists of the 85 following mechanism. The shaft 60 carries a miter gear 137 (Fig. 4) meshing with a complementary gear 138 (Fig. 1) on a transverse shaft 139 on which there is loosely mounted a gear 140 which meshes with a 90 gear 141 on a parallel shaft 142 which carries the sprocket wheels 131. This shaft carries also a control disk 143 having two stop shoulders 144 in its periphery. A latch 145 is pivoted on a pin 146 and has an arm 147 95 which is acted on by a spring 148 so as to press the latch toward the periphery of the control disk, said latch being in the same plane with the disk. The latch also has a finger 149 projecting toward and in the 100 path of a striker 150 on the shaft 139. The gear 140 is frictionally driven by the shaft 139 through a friction disk 151 which may be of wood, or has a wood face next to the gear, and is splined to the shaft and is 105 pressed against the face of the gear by a spring 152 under a pressure which is adjustable by the nuts 153. The force applied to the gear by the friction disk is sufficient to drive the conveyer and the work pieces, 110 but insufficient to break the chain or strip the gear teeth when the disk 143 is arrested by the latch.

It will be understood that the striker 150 is rotated constantly and that upon each 115 rotation it disengages the latch 145 from the adjacent stop shoulder 144. As soon as the latch is thus disengaged the shaft 143 is free to turn, and is turned by the gear 140. When a half revolution of the shaft 143 has 120 been completed, the next stop shoulder is arrested by the latch, which has in the meantime been allowed to return against the control disk by the passage of the striker 150. The work grippers and pushers on the conveyer are properly located and timed with 125 respect to the stop shoulders 144 so as to place a blank properly beneath the presser foot and the knives at each stop of the conveyer.

The mode of operation of the machine will have been made sufficiently clear by the foregoing description of the mechanical parts to make any detailed description of operation unnecessary. It may be observed, however, that the knife carrier and the holder or carrier for the presser fingers are moved up and down simultaneously with the presser foot, thereby moving the knife and presser fingers clear of the work during the feeding movements of the conveyer, and bringing these parts into proper operating relation to the work whenever the presser foot is brought down to clamp the work. As the driving mechanism for the knife actuating levers 40 is constantly in operation, the cams 70 are timed so as to lower the frames carrying the presser foot and the knives into their working location at the instant when the knife carriers are at the inner limit of travel.

The operator's control of the machine is given by the fast and loose belt pulleys 51 and 52, and by the links 39. The operator can start or stop the machine by shifting the belt from one pulley to the other, but after the machine is in operation it is entirely automatic in all respects, including the grasping and releasing of the work by the conveyer, and the starting and stopping of the conveyer. The operator can, however, if there is any occasion for doing so, interrupt the movement of the knife carriers and the work pressers, by disconnecting the carrier actuating link from its actuating lever 40.

The terms "forward" and "front" and words of similar import, when applied to the machine as a whole are intended to indicate the side of the machine at which the attendant stands in placing the work; the terms "rear" "back," etc., signifying the opposite side of the machine. But such terms as "front," "forward," "advance," and the like, used in respect to the conveyer, have reference to the direction in which the conveyer travels. All these, and other terms used in describing the machine, are descriptive terms chosen with reference to their aptness to this particular machine, and have no limiting significance.

What we claim and desire to secure by Letters Patent is:—

1. A cutting machine including two knives mounted to move apart and toward one another, a work support, means for holding the end portions of the work at an inclination to and extending across the paths in which the edges of said knives travel, and means coöoperating with the work support for holding the intermediate part of the work at one side of such paths, whereby the work is cut at both ends on a bevel.

2. A cutting machine including two travel-

ing knives, a work support, said work support including portions arranged to hold the ends of the work piece inclined to and extending across the paths in which the edges of the said knives travel, and means for adjusting said portions to vary the inclination of the ends of the work and the extent of the work which crosses the said paths.

3. A machine for clipping the ends of a counter blank on a bevel comprising a work support and a presser arranged to grip the blank at a distance from its ends, two knives guided to travel from a point near the gripped part of the blank outwardly toward the ends thereof, said knives being arranged with their edges transverse to the direction in which they travel, and means for inclining the ends of the blank so as to cause such ends to cross the paths of the knife edges.

4. A machine for clipping the ends of shoe counter blanks comprising means for grasping the central portion of the blank, two knives arranged on respectively opposite sides of said grasping means and movable outwardly from positions near said means in the directions in which the ends of the blank extend, means for so moving said knives in unison, and means for holding the ends of the blank inclined to and across the paths of the respective knives.

5. A machine for clipping the ends of counter blanks, comprising two knives guided to move in a definite path and each having its edge arranged transverse to its direction of travel, work holding means arranged to support said blank so that a portion thereof crosses the path of each knife edge at an inclination thereto and a yielding presser traveling with each knife in the path thereof arranged to press the work against the support.

6. A cutting machine comprising a work support, a knife carrier arranged to travel over said support, a knife secured to said carrier, and a series of independently yieldable fingers of resilient structure arranged side by side, being supported by the carrier a distance in front of the knife and extending from their point of support toward the knife edge oppositely to the direction of cutting travel at an acute angle to such direction, for holding the work against the support and preventing the same from being raised by the action of the knife.

7. A cutting machine comprising a knife, a work support including a forming plate arranged to support that portion of the work which is acted on by the knife, and a series of fingers arranged closely adjacent to one another in a line approximately parallel to the edge of the knife and each being independently pressed yieldingly toward the forming plate, said knife and fingers being

movable over the work on said plate and the fingers being adapted to conform the work to the surface of said plate.

8. In a cutting machine, guiding means, a 5 knife carrier arranged to travel on said guiding means, a knife block having flanges, said carrier being provided with recesses adapted to receive said flanges in a readily removable manner, clamps for securing said flanges in 10 said recesses, and a knife secured to said block.

9. In a cutting machine, guiding means, a 15 knife carrier arranged to travel on said guiding means, a knife block having flanges, said carrier being provided with recesses adapted to receive said flanges in a readily removable manner, clamps for securing said flanges in 20 said recesses, the knife block having an inclined end wall, and a knife secured to said end wall with its cutting edge projecting beyond an adjacent side wall of the block.

10. In a cutting machine the combination 25 of a carrier, a knife block depending from said carrier and having a knife on its lower end, and work pressing fingers supported by said carrier in advance of said knife, said fingers being arranged in a series approximately co-extensive with the length of the 30 knife and being independently yielding against resilient resistance away from the plane of action of the knife, and said knife block being recessed at the side adjacent to said fingers and inclined forwardly in the direction of cutting travel to provide a forwardly discharging passage for escape of 35 chips cut by the knife.

11. In a cutting machine the combination 40 of carrier, a knife block depending from said carrier and having a knife on its lower end, work pressing fingers supported by said carrier in advance of said knife, said fingers being arranged in a series approximately co-extensive with the length of the 45 knife and being independently yielding against resilient resistance away from the plane of action of the knife, and a cover plate overlying said fingers to prevent chips from lodging between the fingers, a passage being provided between said plate and the 50 knife and knife block to permit escape of chips.

12. In a cutting machine the combination 55 of a work support having its supporting surface formed according to the character desired to be given to the surface produced by cutting in the work, a knife carrier arranged to travel over said work support, a knife fixed to said carrier, a pivot rod secured to said carrier in advance of the 60 knife and means for applying pressure independently to numerous closely adjacent localities of the work in advance of said knife, whereby to conform the work closely to the surface of said support, said pressure- 65 applying means comprising a series of in-

dependently yielding fingers pivoted on said rod, each having a resilient arm, and a fixed abutment against which said arms bear.

13. In a cutting machine, a knife guided to travel with its edge in a given plane, and 70 a work support comprising holding means adapted to grasp a portion of the work and adjustable supporting means arranged to hold another portion of the work across said plane and at an inclination thereto, said 75 means being adjustable transversely to said plane.

14. In a cutting machine, a knife guided to travel with its edge in a given plane, and 80 a work support comprising holding means adapted to grasp a portion of the work, adjustable supporting means for holding another portion of the work at an inclination to the grasped portion and to said plane, and means for so moving said supporting 85 means as to alter the angle between said other portion and said plane.

15. In a cutting machine, a work support 90 adapted to support a portion of the work piece, a presser foot for holding the work against said support, an adjustable support for supporting another part of the work, said adjustable support being movable transversely to the surface of the work piece, and a knife guided to travel with its edge in 95 a plane substantially parallel to said surface.

16. In a cutting machine, a support adapted to support a portion of the work piece, a 100 plate adjoining said support, over which a part of the work is adapted to extend, and an adjusting member engaging said plate and operable to displace the edge thereof most remote from said support in such manner as to alter the inclination of the supporting surface of the plate to said support. 105

17. In a cutting machine, a support adapted to support a portion of the work piece, a 110 plate adjoining said support over which a part of the work is adapted to extend, and an adjusting member on which the opposite side of said plate from the supporting surface near the edge most remote from said support thereof bears, said member being movable to alter the inclination of the plate 115 to said support.

18. In a cutting machine, clamping means adapted to grasp part of the work piece, a 120 plate adjacent to said clamping means having a surface over which the work piece may project and lie, and adjusting means bearing on the side of said plate opposite to said surface and in proximity to the opposite edges of the plate, the construction and arrangement being such that movement of said 125 adjusting means may shift the parts of said plate on which they respectively bear transversely to the direction in which the work piece extends.

19. In a cutting machine, a work sup- 130

- porting plate having a yielding means for anchoring its central portion, and independently adjustable means adapted to displace the opposite edge portions of said plate in a direction transverse to the plane of the plate.
20. In a cutting machine in combination with a knife guided and operated to travel with its edge in a fixed plane, a work supporting plate adapted to hold work extending across such plane at an inclination thereto, and means for altering the position of the plate as a whole, and also its inclination, with respect to said plane.
- 15 21. In a cutting machine, a work supporting member mounted with capacity for movement transversely to the plane of its supporting surface and adjusting members arranged to act on said work supporting member adjacent to the opposite edges thereof and independently operable to shift the portions of the supporting member on which they act transversely to the supporting surface of said supporting member.
- 20 22. In a cutting machine, a work support mounted with capacity for movement transversely to its supporting surface, adjusting wedges underlying the opposite edge portions of said support, and means for shifting said wedges whereby to vary the position and inclination of said support.
- 25 23. In a cutting machine a work supporting plate having inclined faces near its opposite edges at the side opposite to the supporting surface thereof, and being mounted with capacity for movement transversely to such surface and adjusting members engaging said inclined faces and being movable independently of one another in directions approximately parallel to the plane of the supporting surface, whereby to shift and tilt said plate to the desired extent.
- 30 24. In a cutting machine the combination with a table of a work supporting plate mounted loosely on said table, adjusting members underlying the opposite side edges of said plate and movable across the table, said plate having inclined surfaces engaged by said members, respectively, and independent adjusting means for shifting said members independently of one another whereby to lift the plate to a greater or less extent at different parts thereof and thereby vary the height and inclination of the plate.
- 35 25. In a machine for bevel cutting the ends of a counter blank, the combination with means for supporting a counter and a presser foot arranged to bear upon the middle part of the counter, of knives located at each side of said presser foot, mechanism for moving said knives simultaneously away from said presser foot, and means for holding the opposite end portions of the blank to cross the paths of the respective knives at
- 5 26. In a cutting machine the combination with a work support, of a knife carrier, a guide on which said knife carrier is adapted to travel in directions approximately parallel to the work support, and means for shifting the guide and therewith the knife carrier away from the support to permit placing of work pieces, and toward the support into cutting position.
- 10 27. In a cutting machine, two knife carriers, guides on which said knife carriers are supported and guided to move in line with each other, an operating lever linked to each of said carriers and mechanism for oscillating said levers simultaneously to move said carriers toward and away from one another.
- 15 28. In a cutting machine, the combination with a work support of a frame supported over said work support and movable up and down, laterally extending guiding means on said frame, a knife carrier supported and movable on said guiding means, mechanism for raising and lowering said frame and mechanism for moving said knife carrier back and forth, said mechanisms being so timed as to cause the knife carrier to move in one direction when the frame is raised and in the opposite direction when the frame is lowered.
- 20 29. In a cutting machine, a knife carrier, a guide on which said carrier is movably mounted, a frame or holder carrying said guide and being movable in a direction transverse to that in which the knife carrier moves on said guide, and mechanisms for moving said frame or holder back and forth between two positions and for moving said knife carrier back and forth, respectively, said mechanisms being so timed as to move the knife carrier in one direction when the frame is in one of said positions, and in the opposite direction when the frame is in the other of said positions.
- 25 30. In a cutting machine, the combination with a main frame of a movable secondary frame including guide members, a knife carrier mounted on said guide members, and having a recess with shoulders at each end thereof, a clamp member connected to each of said shoulders extending therefrom across the adjacent ends of the recess, a knife block constructed to enter said recess and having flanges at its ends arranged to pass between said clamps and the body of the carrier, and a knife secured to said knife block.
- 30 31. In a cutting machine, a knife carrier movably mounted, an actuating lever for moving said knife carrier and a link joining said carrier and lever, the link having a hook portion engaged with said lever and
- 35 40 45 50 55 60 65 70 75 80 85 90 95 100 105 110 115 120 125 130

adapted for instant disengagement therefrom.

32. In a cutting machine, the combination with a base, of upright rods passing through said base and arranged in pairs, parallel beams secured to the members of each pair of rods, and a cross tie secured to said beams, and a presser foot mounted on said cross tie extending toward said base and being yieldingly projected toward the same.

33. In a cutting machine, the combination with a base, of upright rods passing through said base and arranged in pairs, parallel beams secured to the members of each pair of rods, and a cross tie secured to said beams, a presser foot mounted on said cross tie extending toward said base and being yieldingly projected toward the same, a guide supported by each pair of rods, a knife carrier mounted on said guides beside said presser foot and a knife block having a knife at its extremity projecting from said carrier toward the base.

34. In a cutting machine the combination with a knife carrier, a knife block projecting from said carrier having a knife at its extremity, a presser holder secured to said knife carrier and having a pivot rod, and presser fingers arranged side by side on said rod and extending therefrom toward the edge of said knife.

35. In a cutting machine, the combination with a knife carrier and a knife mounted thereon, of a holder connected to said knife carrier and having a pivot rod, presser fingers mounted side by side on said rod and extending therefrom toward the knife, each of said fingers having a resilient extension, and an abutment connected to said holder and engaging the extensions of said fingers.

36. In a cutting machine, the combination with a knife carrier and a knife mounted thereon, of a holder connected to said knife carrier and having a pivot rod, presser fingers mounted side by side on said rod and extending therefrom toward the knife, each of said fingers having a resilient extension, and an abutment connected to said holder and engaging the extensions of said fingers, said abutment being arranged between said extensions and the plane of action of the knife, whereby to resist movement of the fingers away from such plane.

37. In a cutting machine having a knife, a work support, a carrier holding said knife, one of the parts constituted by said carrier and support being movable relatively to the other for cutting, and means for pressing the work against the support comprising a series of pressers pivoted side by side to the knife carrier at the side thereof toward which the knife acts in cutting, and extending from their pivot axis on a slant toward the work support, each of said press-

ers being freely and independently movable about such axis and provided with a resilient finger, and an adjustable abutment against which said fingers bear arranged in position to oppose movement of the pressers away from the work support.

38. In a cutting machine having a knife, a contrivance for pressing on the work in advance of the knife consisting of a holder, a pivot rod mounted on said holder, a series of fingers arranged side by side on said pivot rod and each finger having a resilient extension, and a rigid abutment connected to said holder against which said extensions bear.

39. An automatic cutting machine comprising a work support, a cutting knife, a work conveyer, means for moving said work conveyer intermittently and causing the same to pause with a blank upon said work support, a presser arranged over the work support, means for urging the presser toward the work support while the work piece is in position thereover, and means for moving the knife while the work is so held.

40. In a cutting machine in combination with a work support, a means for holding work on said support comprising a frame, guide rods projecting from said frame toward the work support, a presser foot movably mounted on said guide rods, a yoke rigidly connected to said presser foot and adapted to rest on said frame, and springs yieldingly pressing said yoke toward said frame, whereby the presser foot is yieldingly projected toward the work support.

41. In a cutting machine, the combination with a work support, of means for clamping work thereon, comprising a frame holder mounted over the support and movable toward and away from the same, a presser member having portions resting on said holder and having another portion projecting toward the work support, and being movable away from the support relatively to the holder, and a spring acting on said presser member to urge the same toward the support.

42. In a cutting machine, the combination with a work support, means for clamping the work thereon, comprising a holder movable toward and away from the support, a presser foot between said holder and work support, a yoke rigidly connected to said presser foot and overlying portions of the holder away from the work support, guide rods rigidly carried by the support on which the presser foot and yoke are guided to move toward and away from the work support, abutments on said guide rods, and springs interposed between said abutments and the yoke acting to press said yoke toward the adjacent part of the holder and to project the presser foot from the holder toward the work support.

43. A cutting machine comprising a work support, a presser for holding pieces on said support, a movable knife adapted to cut the work pieces so held, an endless conveyer for placing the work pieces on the support, a main shaft, mechanism by which said main shaft moves said presser toward the work support, mechanism by which said shaft operates said knife, and intermittently acting means operated by the shaft for driving the conveyer.

44. A cutting machine comprising means for holding a work piece, a movable knife, an endless conveyer for transporting work

15 pieces to said holding means, a main shaft, mechanism driven by said shaft for moving the knife, and intermittently acting mechanism operated by said shaft for driving the conveyer, arranged and operating to cause 20 the conveyer to stand still while the knife operates, and to move the conveyer while the knife is inoperative.

45. A cutting machine comprising means for holding a work piece, a movable knife, 25 an endless conveyer for transporting work pieces to said holding means, a main shaft, mechanism driven by said shaft for moving the knife, a second shaft driven by the main shaft, a gear frictionally held on said second 30 shaft, connections through which said gear drives the conveyer, means arranged to arrest the gear when the knife is actuated to cut, and means for disabling said arresting means when the knife is inoperative, where- 35 by the gear is enabled to move the conveyer at such times.

46. A cutting machine comprising means for holding a work piece, a movable knife, an endless conveyer for transporting work 40 pieces to said holding means, a main shaft,

mechanism driven by said shaft for moving the knife, a second shaft driven by the main shaft, a gear on the second shaft frictionally clutched thereto to turn therewith and arranged to drive the conveyer, a disk having a stop shoulder, driven by said gear, a stop adapted to engage said stop shoulder to arrest the disk and gear, and a member secured to the second shaft arranged to displace said stop; the stop shoulder being located to engage the stop when the knife operates, and the stop-displacing member being arranged to act as set forth when the knife is inoperative.

47. A cutting machine comprising means 55 for holding a work piece, a movable knife, an endless conveyer for transporting work pieces to said holding means, a main shaft, mechanism driven by said shaft for moving the knife, a second shaft driven by the main 60 shaft, a gear on the second shaft frictionally restrained from rotation relatively thereto, a third shaft driven by said gear and engaged with the conveyer to drive the latter, a stop disk mounted on the third shaft and 65 having a stop shoulder, a complementary stop arranged to engage said shoulder and arrest the third shaft when the knife is operated, and a member carried by the second shaft arranged to displace said stop from engage- 70 ment with the shoulder when the knife is inoperative.

In testimony whereof we have affixed our signatures in presence of two witnesses.
